BRACING DEVICE FOR SILOS.

1,152,174.

Specification of Letters Patent. Patented Aug. 31, 1915.

Application filed September 19, 1914. Serial No. 862,565.

To all whom it may concern:

Be it known that I, THEODORE M. HAMILTON, a citizen of the United States, and a resident of Fairfax, in the county of Fairfax and State of Virginia, have made certain new and useful Improvements in Bracing Devices for Silos, of which the following is a specification.

My invention relates to improvements in silos, and it consists in the combinations, constructions and arrangements herein described and claimed.

The device is particularly designed for use with wooden silos of the type in which a series of staves is held together by retaining bands on the outside of the silo after the manner of the so-called barrel construction.

Silos constructed of wood are especially useful in certain parts of the country owing to the fact that they are easily set up, and are comparatively inexpensive. Those constructed of staves which are held together by external bands or hoops are, however, subject to collapse due to the fact that in wet weather the wood will absorb moisture, thereby swelling, while in dry weather the wood will shrink and tend to draw away from the outside bands. This necessitates the tightening of the bands. As soon as the silo is full so that there is pressure on the inside the structure is in no danger of collapsing, but as the silage is used up and is withdrawn from the interior sudden wind which exerts considerable pressure on one side may tend to cause the structure to collapse, due to the fact that the staves are forced inwardly.

An object of my invention is to provide means whereby a silo of the type described may be braced internally so that even if it is empty there will be no danger of the device collapsing.

A further object of my invention is to provide means for bracing the interior of a silo, which is easily adjustable, so that as the silo is filled the bracing device may be removed and as the silage is used it may be again brought into use.

A further object of my invention is to provide a bracing device which is comparatively cheap to manufacture but which amply fulfills the purpose for which it is designed.

Other objects and advantages will appear in the following specification, and the novel

features of the invention will be particularly pointed out in the appended claims.

My invention is illustrated in the accompanying drawings forming part of this application in which,

Figure 1 shows a vertical section through the silo and the bracing device along the line 1—1 of Fig. 2, Fig. 2 is a plan view of the bracing device, and Fig. 3 is an enlarged detail view partly in section of a portion of the bracing device.

In carrying out my invention I make use of a circular brace member made up preferably of a series of segments of piping, such as gas pipe or water pipe. In Fig. 1 I have shown five such segments at 1, 2, 3, 4 and 5 respectively, although it is obvious that a greater or less number may be used without departing from the spirit of the invention. These segments when placed together end to end are designed to just fit within the interior of the silo, being held together by the holding means about to be described.

From an inspection of Fig. 3 it will be seen that I provide at the end of the pipe sections a T-shaped joining member 6 having reduced portions 6^a arranged to enter the end of adjacent pipe sections, such as those shown at 2. The joining member 6 is also provided with a lateral extension 6^b which is designed to enter the end of a hollow brace member 7, being preferably secured in position by means of a bolt 8. A central casting 9 is provided with radially extending ears 10 between which the end 11^a of a companion brace member 11 extends. Bolts 12 are provided for pivotally securing the companion brace member 11 to the casting 9. A shoulder 11^b is provided on each of the extensions 11^a for limiting the pivotal movement, as will be explained later. The brace members 7 are connected with the brace members 11 by means of an expansion joint 12 in such a manner that the members 7, 11 and 12 form in fact a continuous brace member extending laterally from the central casting 9 and connecting with the joining member 6. Between the ends of two of the pipe sections I dispose a turnbuckle 13, the purpose of this turnbuckle being to expand or contract the ring made by the pipe sections 1, 2, 3, etc.

From the foregoing description of the various parts of the device the operation there-

of may be readily understood. We will assume that the silage has been used up to a point which necessitates the bracing of the upper part. The bracing device may be introduced into the upper part of the silo in sections. That is to say the pipe members 1, 2, 3 and 4 may be placed inside of the silo and the joining members 6 fitted to their ends. The ring thus formed is placed in the silo in such a manner that the ring engages the sides 14 of the silo, as shown in Fig. 1. The turnbuckle 13 may now be tightened so as to expand the ring, thereby holding it frictional against the sides. The 15 radially extending brace members may now be secured to the joining members 6 by means of the bolts 8 and the expansion members 12 are so turned that the casting 9 takes a position which is slightly above the plane 20 of the ring or pipe, as shown in dotted lines in Fig. 1. Now by forcing the casting downwardly the radially extending brace members will tend to be thrust outwardly, thereby bracing the ring or pipe. The 25 shoulders 11^b are designed to engage the top of the casting 9, as shown in Fig. 1, so as to limit the downward movement of the latter. The casting is now very slightly below the plane of the ring or pipe, and this locks 30 the casting in position, since any external pressure tends to force the casting down while the shoulder prevents any further downward movement. If now, there should be undue pressure from the outside, as that 35 caused by wind pressure, or from tightening the exterior bands of the silo, the latter will be kept from collapse by the brace on the inside. As the silage is used up, the position of the bracing device may be shifted 40 by forcing the casting 9 forwardly to its dotted line position, thereby withdrawing the radial pressure and loosening the turnbuckle. The bracing device may then be lowered to a position where the turnbuckle 45 may be again tightened up and the central casting again forced down, in the manner heretofore described. When it is again desired to fill the silo the turnbuckle may be loosened, the brace members unlocked and 50 the ring or pipe together with the brace members may be drawn bodily upward, as for instance by a pulley, not shown, located at the top of the silo. If no pulley is to be had the bolts 8 may be removed and the ring 55 of pipe lifted bodily and secured in position by tightening the turnbuckle. I contemplate, of course, the use of one or more of these bracing devices for each silo. The distance through which the central casting must 60 be forced in order to lock the device would depend, of course, upon the size of the silo and of the bracing device. In actual practice the vertical distance between the extreme positions of the central casting in the 65 locked and unlocked positions, that is to say

the vertical distance between the dotted and full line positions shown in Fig. 1, would be relatively small. In the drawings I have exaggerated this distance in order to clearly show the operation of the device. After the 70 expansion joints 12 are once set for the proper distance it will only be necessary to change them on rare occasions.

The device thus described comprises a cheap and thoroughly efficient means of 75 bracing the interior of the silo. The parts are of comparatively light weight but are so arranged as to brace the device along lines in which the strain is apt to occur, that is to say along radial lines.

I claim:

1. In a bracing device for silos, an expansion ring arranged to engage the interior walls of the silo, radially extending brace members connected to said ring, each of said 35 radially extending brace members being independently expansible, and a central holding member pivotally secured to said brace members for simultaneously locking the brace members in position.

2. In a bracing device for silos, an expansion ring arranged to engage the interior walls of the silo, radially extending brace members connected to said ring, each of said 95 radially extending brace members being independently expansible, and a central holding member pivotally secured to said brace members for simultaneously locking the brace members in position, said central holding member comprising a ring having laterally extending ears for pivotal connection with the brace members.

3. In a bracing device for silos, a ring comprising a series of pipes jointed together and adapted to engage the interior walls of 105 the silo, a central holding member, a series of bracing members pivotally connected to said holding member at one end and being pivotally connected to said ring at the other end, and means carried by each of said bracing members for increasing or decreasing its effective length.

4. In a bracing device for silos, a ring comprising a series of pipes jointed together and adapted to engage the interior walls of 115 the silo, a central holding member, a series of bracing members pivotally connected to said holding member at one end and being pivotally connected to said ring at the other end, means carried by each of said bracing members for increasing or decreasing its effective length, said central holding member being movable with respect to the ring, whereby the radially extending brace members are thrust outwardly, and means for locking the holding member in its shifted position.

5. In a bracing device for silos, a ring comprising a series of pipes jointed together and adapted to engage the interior walls of 130

the silo, a central holding member, a series of bracing members pivotally connected to said holding member at one end and being pivotally connected to said ring at the other end, means carried by each of said bracing members for increasing or decreasing its effective length, said central holding member being movable with respect to the ring, whereby the radially extending brace members are thrust outwardly, and means for

locking the holding member in its shifted position, said last-named means comprising shoulders on the brace members arranged to engage the holding member when the latter has passed beyond the plane of the ring.

THEODORE MARION HAMILTON.
